UNITED STATES PATENT OFFICE.

GEORGE H. RUMKE, OF DENVER, COLORADO.

AMUSEMENT APPARATUS.

Application filed December 18, 1922. Serial No. 607,533.

The object of this invention is to provide amusement apparatus which shall be particularly adapted for use in various types of traveling shows for the performance of 5 gymnastic feats. The present invention is an improvement over that covered in my former Patent No. 1,256,734 of February 19, 1918.

The invention comprises a flexibly suspended support such as a trapeze bar which is adapted to rotate about an axis and is parallel with such axis, means being provided to cause a performer to be swung about the axis at the end of said support and 10 to describe a complete circle under influence of centrifugal force. In various forms, the performer may be caused to describe a circle of fixed radius, or to swing one or more times completely around said axis on gradually increasing radii or radii working from 15 separated centers. The trapeze works in conjunction with a propelling member which engages either the performer or the ropes of the trapeze to produce the desired impulse, and in one form the propelling member 20 may carry a net to stop the performer after having passed over the top of the circle and reached the lowermost point thereof. In one form a rigid trapeze may be driven 25 about the circle.

In the accompanying drawings wherein certain embodiments of the invention are disclosed,

Fig. 1 is a side view of one form taken 35 from line 1—1 of Fig. 2;

Fig. 2 is a front view taken from line 2—2 of Fig. 1;

Fig. 3 is a detail showing a modification 40 for increasing the radius;

Fig. 4 is a perspective view showing a rigid trapeze;

Fig. 5 is a detailed section taken on line 5—5 of Fig. 3;

Fig. 6 is a side elevation of another form 45 having a net;

Fig. 7 is a detail taken from line 7—7 of Fig. 6, the net being shown in lowermost position on the propelling frame which carries it;

Fig. 8 is a modification of the form of 50 Fig. 6 for increasing the radius of movement, the net being dispensed with.

Figs. 9 and 10 are side and front elevations respectively of forms of the device 55 embodying all of the important features of the other forms.

All forms are shown as being particularly adapted to circus tents or to theatrical stages wherein suitable supporting blocks 10 or the like for the moving portion of the apparatus are properly positioned or suspended by means of guy wires or ropes 12 connected with the floor or ground below as by means of stakes 14 or the like and with any convenient point of attachment above. 60 The blocks 10 carry the axle 15 which directly carries the moving parts.

In the form of Figs. 1 and 2, a sleeve 16 is mounted on axle 15, and the ropes 18 which carry the trapeze bar 19 are connected with the ends of said sleeve. The performer 20 thus will be loosely carried by the axle 15, and he starts his movement by swinging back and forth until he reaches as high a point in the direction of the arrow α 65 as possible. On the last stroke in the direction of said arrow, the cross bar 22 of a rotary frame 21 is driven against the ropes 18 of the trapeze thereby adding to the swinging motion that impulse which is necessary to carry the performer over the top 70 of the circle, his position at the end of the trapeze being maintained under influence of centrifugal force. The frame 21, which is journaled on axle 15 is driven by means of a pair of large pulleys 24 over which there passes a belt preferably hand driven by means of a crank 26 or by pulling on the belt itself. Thus power may be applied to the belt 25 and frame 21 at just the moment 75 desired by attendants. After swinging over the axle the performer is stopped, preferably, by means of a net, 34, placed in his path by attendants.

In Figs. 3 and 5 there is indicated a slight modification of the form of Figs. 1 and 2. Here the ends of the trapeze rope 18 are wrapped around the axle 15 a number of times as indicated at 118 and are secured to said axle. Thus for each complete circuit 80 around the axle the ropes 18 will unwind from said axle one turn allowing the radius upon which the performer swings to increase gradually. In this manner the performer may start from a point close to the cross bar 22 of the frame 21, and finish at a considerable distance therefrom. In these forms the performer will be stopped by means of a net drawn by attendants into his path of movement at a low point. 85

In Fig. 4, the frame and trapeze are combined into a single rigid device 119 carry-

ing the trapeze bar 19, this device being driven directly by the pulleys 24 and belts 25. Since the rigidity of the arms 119 would prevent the performer from falling vertically after cessation of centrifugal force, a net would not be required to stop the swing of the performer although it can be used or the oscillatory movement could be allowed to stop gradually or could be stopped by means of the belt 25, or the performer could leap from bar 19 as it approached the ground if he wished.

Figs. 6 and 7 show a form of the device in which the performer starts from the top-most point of the circle and is stopped by a net automatically interposed, the performer being then swung over the top of the circle only once. Here the trapeze ropes are swingingly connected with axle 15 by means of clips 30, and a pair of rigid poles or arms 33 are journaled on said axle by bearings 32. Arms 33 constitute a propelling device and carry between them a net 34 whereby a stopping device is provided also. Some means such as rests indicated at 35 in Fig. 6, is provided on the arms 33, to which the performer may mount and upon which he may be supported with said arms in the elevated position shown in Fig. 6. For the purpose of maintaining the arms 33 upright they are provided with suitable catches 36 operable by the performer through the means of cords 37, said catches 36 being adapted for engagement by restraining cables 38 on one side of said arms. Cables 40 extend from the other side of said arms and may pass around pulleys to more or less powerful springs 44 which exert a strong pull on said arms. When the cords 37 are actuated to withdraw the catches 36 from the cables 38, the springs 44 forcibly pull the propelling frame, which is composed of arms 33 and net 34, downward with the performer and the trapeze 18 in advance thereof. The power of said springs 44, or other suitable power means connected to cables 40, is sufficient to drive the performer upon the trapeze up from the lowermost point of the circle and over the top thereof and down again with the trapeze taut. Braking means such as cables 45 secured to supports 46 are connected to the arms 33 so as to stop their movement when they reach approximately lowermost position as seen in dotted lines and also to spread the arms and stretch the net 34 as seen in Figs. 6 and 7 respectively. Thus the net is automatically positioned in the path of the performer to stop him after having been propelled over the top of the circle and upon reaching the bottom thereof again; supports 46 are spaced as shown.

A modification of the form of Figs. 6 and 7 is disclosed in Fig. 8 wherein the net is eliminated and the top of a tent T is employed to stop the performer. Here arms 50

are mounted upon the axle 15 as are the arms 33 and the performer is adapted to be supported upon rests 52 like rests 35. However the trapeze ropes 53 are wrapped once around to axle 15 and the ends are then passed upward and secured adjacent the top of the tent at 54. The means of Fig. 6 or other suitable means is employed for releasing and actuating the arms 50, which are spread and drawn out of the way by cables 55 like cables 45. Here the performer swings around the axle and unwinds the ropes 53 from axle 15 after passing over the top of the circle, so that as he passes the lowermost point his center of motion is transferred to the point of attachment 54. This causes him to strike the canvas top of the tent T and be stopped thereby.

In any of these forms, a rope may be provided on the trapeze bar 19 to pass around the shoulders of the performer when he is hanging from his knees. This insures against his being thrown from the bar. Such a rope is shown in Fig. 2 at 60.

A form which embodies all of the important features of the other forms is disclosed in Figs. 9 and 10. Here the axle 15 is supported on blocks 10 or the like by means of guy wires 12, and the trapeze ropes 18 carrying the bar 19 are wrapped around the axle at 118 for unwinding therefrom as in the form of Figs. 3 and 4. The poles or arms 33 of Figs. 6 and 7 are mounted on the axle 15 by being pivotally connected at 65 to blocks 68 secured to the axle. Blocks 68 are secured to drums 124 corresponding to the pulleys 24, and the driving belt 25 is wound about each drum for driving the same through the crank 26. In this manner the belt 25 may be made to control the movements and the position of the arms 33 and their net 34 through the crank 26. The performer 20 will be driven in front of the arms 33 and net 34 as the crank is turned, the performer starting from the top where arms 33 are held by belt 25 and crank 26 initially. As the device is rotated the ropes 18 will unwind. By stopping the crank 26, arms 33 will be stopped and net 34 may be thereby disposed at the bottom as indicated in dotted lines in Fig. 10, the arms 33 having been spread from converging position. The performer is propelled over the top of the circle on the last round and is then stopped by the spread net 34.

Thus, it will be seen that I have provided means for propelling a flexible trapeze about an axis, throwing a performer over the axis, increasing the radius of movement, and stopping the performer.

I claim:

1. Amusement apparatus having an axle, a trapeze having a bar adapted to swing about said axle, a propelling device rotatable about said axle to propel the trapeze over

said axle, and an obstruction adapted to be automatically disposed in the path of the trapeze to stop a performer on the trapeze.

2. Amusement apparatus comprising a fixed horizontal axle, a flexible trapeze initially wound on said axle and adapted to have its radius increased as it swings around said axle, and a propelling device rotatable about said axle to propel said trapeze, and

10 performer thereon, around said axle.

3. Amusement apparatus comprising a horizontal axle, a support for a performer and a propelling device for said support rotatable about said axle and temporarily mounted upright above said axle, and means to give the propelling device an impulse to propel the performer over said axle at a velocity sufficient to be kept from falling by centrifugal force.

29 4. Amusement apparatus comprising two axes, a flexible support for a performer adapted to swing about first one and then the other of said axes and a propelling device for said support rotatable about one of said axes to propel said support and performer over one of said axes at a velocity sufficient to be kept from falling by centrifugal force.

5. Amusement apparatus having an axle, a flexible trapeze connected with the axle and adapted to swing therearound, and a propelling frame to engage the trapeze and drive the same to cause the trapeze to pass over the axle, said frame being adapted to disengage the trapeze.

6. Amusement apparatus comprising a horizontal axle, a temporary rigid support for a performer above said axle rotatable about said axle, and mounted at an approximately vertical position above said axle, means to substantially hold it in, and to release it from, that position at will, and a second support rotatable about said axle adapted to support said performer below said axle.

7. Amusement apparatus having an axle, a trapeze connected with the axle and adapted to swing therearound, and a propelling member mounted on the axle and adapted to engage the trapeze to drive the same and to disengage the trapeze as desired.

8. Amusement apparatus having an axle, a trapeze connected with the axle and adapted to swing thereabout, said trapeze being flexible and having a bar parallel to said axle, and a propelling frame engaging the trapeze to drive the same over the axle.

9. Amusement apparatus having an axle, a flexible trapeze connected with the axle and adapted to swing therearound, and a propelling member to engage the trapeze and drive the same over the axle.

10. Amusement apparatus comprising an axis, a flexible support for a performer adapted to swing around said axis, and a propelling member for engaging said support to drive the same over said axis.

11. Amusement apparatus having an axis, a flexible support for a performer adapted to swing around said axis, means to propel the flexible support, and means in the path thereof to intercept the performer.

12. Amusement apparatus having an axle, a flexible support adapted to swing around said axle and connected therewith in such manner as to unwind from said axle as it swings around the axle for increasing the radius of movement of support, and propelling means for engaging and driving the support over said axle.

13. Amusement apparatus comprising an axis, a flexible support for a performer rotatable about said axis, a propelling member behind said support to propel said support, and performer thereon, over said axis at a velocity sufficient to be kept from falling by centrifugal force, and means to actuate said propelling member.

In testimony whereof I affix my signature.

GEORGE H. RUMKE.
